UNITED STATES PATENT OFFICE

MAURICE ANDERSON, OF EDGEWOOD, RHODE ISLAND, ASSIGNOR TO LEVY, ANDERSON CO., INC., A CORPORATION OF RHODE ISLAND

FOLDABLE BUCKLE

Application filed July 18, 1932. Serial No. 623,210.

This invention relates to a foldable buckle and has for one of its objects to provide means for securing the bracelet end to the buckle in different positions of adjustment.

5 Another object of this invention is the provision of holding means between one of the buckle sections and a member pivoted thereto for securing a variety of different adjusted positions of the bracelet chain in

10 its connection to the buckle.

Another object of this invention is the provision of different catches, any one of which the chain may engage, some of which are on one part and some on another part 15 swingable relative thereto, the parts cooperating to maintain the chain in engagement with a selected desired catch for its adjusted position.

20 A further object of the invention is the provision of an adjustable construction in a position where it will be maintained in securing position by the folding of the sections of the foldable buckle one over the other, requiring an unfolding of the sections 25 to permit of different adjustments.

With these and other objects and advantageous features in view, the invention consists of a novel arrangement of parts more fully disclosed in the detailed description 30 following, in conjunction with the accompanying drawing, and more particularly set forth in the appended claims.

In the accompanying drawing:—

Fig. 1 is a top plan view of the buckle in 35 folded position.

Fig. 2 is a top plan view of the buckle in extended unfolded position and exposing the adjustment means.

Fig. 3 is a perspective view of the end or 40 body section of the buckle.

Fig. 4 is a perspective view of the pivoted member for retaining the end link of the chain in adjusted position.

Fig. 5 is a perspective view of the section 45 shown in Fig. 3, and the member in Fig. 4, as assembled with the member raised from closed position to expose the adjustment parts and the end of a bracelet chain connected therein.

50 Fig. 6 is a perspective view of a typical

end link of a chain which may be attached to this buckle.

Fig. 7 is a central sectional view through the device on substantially line 7—7 of Fig. 1.

55 In the use of foldable buckles, it is frequently desirable to adjust the encircling size of the bracelet in which the buckle is used so that an adjustment less than the length of one of the links may be had, and 60 in order to accomplish this result I have raised hooks or abutment members on the body section and provide a pivoted member to close down over these hooks and maintain a bracelet link in engagement with a selected 65 one of these hooks to obtain the desired adjustment, and in order that an adjustment may be provided between these hooks I have provided fingers on the closure member, 70 back of which the link may also engage to provide an additional adjustment between the hooks; and the following is a detailed 75 description of the present embodiment of this invention illustrating the preferred means by which these advantageous results may be accomplished.

With reference to the drawing, 10 designates the body section at one end of the buckle and 11 the cover section at the other end of the buckle, which sections are hinged 80 together by an intermediate section 12 pivoted to the two end sections by means of trunnions 13 and 14 extending outwardly into the channel walls of these end sections. One end link 15 of the bracelet chain is secured to the end section 11 by means of a tongue 16 rolled about a cross bar at the end of the link 15, while the other end 17 of the bracelet chain is adjustably connected 85 to the opposite end section 10 by engagement 90 with any one of several different abutments to secure it in adjusted position.

95 At the end of section 10 there is folded up a hook 18 and also there is cut and raised a hook 19 from the stock of the bottom wall of this section located inwardly from the end hook 18 and back of either of which hooks the end link 17 may engage. I have also provided a cover or closure member 20 pivoted by means of trunnions 21 in the side 100

walls 22 of the section 10, which member lies closely along the bottom wall of the body section 10 a short distance and is then offset as at 23 to extend up and over the hook 19 and the hook or curved tongue 18 and is provided with a hook or curved tongue 24 at its end to spring outwardly over the hook or curved tongue 18 and frictionally engage therewith to maintain the member in closed position. I have also provided on this member, fingers 25 on either side which extend to a point substantially in contact with the bottom wall of the member 10 when the member is in closed position, and these fingers are positioned intermediate of the two hooks 18 and 19 so that the end link 17 may engage back of these fingers and be held in this additional position of adjustment with relation to the end section 10.

20 Thus it will be seen that I may cause the end cross bar 26 of the end link 17 to engage either the hooks 18 or 19 or back of the fingers 25 and be held in any one of these three adjusted positions when the member 20 is in closed position, and from this arrangement it will be seen that I may easily adjust the end link to any one of these positions to vary the encircling sizes of the bracelet when in contracted position.

30 The side walls 22 of the channel section 10 are notched as at 30 to receive the trunnions 14 of the intermediate section and permit the device to lie in closely housed position that the same may be of a minimum thickness, which is desired in structures of this character.

35 The intermediate section 12 and cover section 11 when in folded position overlie the member 20 and by reason of the recesses 27 and cooperating detents in the cover member 11 these parts are held in folded position and positively lock and prevent the member 20 from being opened to permit release of the bracelet from its different positions 45 of adjustment.

40 The sections of the bracelet are made of light thin stock and are grooved and ribbed as at 28 and 29 to stiffen the same and prevent bending of the parts out of alignment.

50 It is of course understood that I may provide additional fingers besides those shown at 25, or a different number of hooks may be had, all which will function in the manner above indicated. The member and the section cooperating to confine the bracelet in the adjusted and desired position.

55 The foregoing description is directed solely towards the construction illustrated, 60 but I desire it to be understood that I reserve the privilege of resorting to all the mechanical changes to which the device is susceptible, the invention being defined and limited only by the terms of the appended 65 claims.

I claim:

1. In a foldable buckle, a section provided with a curved tongue, a pivoted member in said section to confine a bracelet link between it and the section and provided with a curved tongue to snap over the first tongue and hold the member in closed position, a second section hinged to the first section to fold over the said member and the first said section and maintain said member in link 70 confining position.

2. In a foldable buckle, a section, a pivoted member in said section to confine a bracelet link between it and the section and adjustment means partly on said section and partly on said member with which the bracelet link may selectively engage to determine its position, and a second section hinged to the first section to fold over said section and 80 cover the said member and maintain the member in link confining position.

3. In a foldable buckle, a section provided with a curved tongue, a pivoted member in said section to confine a bracelet link between it and the section provided with a curved tongue to snap over the first tongue and hold the member in closed position, and means along the edge of said member spaced from the end thereof and back of which the link engages to position it inwardly from the end of said member, and a second section hinged to the first section to fold over the said member and maintain it in link 90 confining position.

4. In a foldable buckle, a section, a pivoted member in said section to confine a bracelet link between it and the section, and adjustment means partly on said section and partly on said member with which the bracelet link may selectively engage to determine its position, said means including portions integral with the section extending toward the member and portions integral with the member extending toward the section back of which the link may engage, and 100 a second section hinged to the first section to fold over the said member and maintain it in link confining position.

5. In a foldable buckle, a section, a pivoted member in said section to confine a 110 bracelet link between it and the section, and adjustment means partly on said section and partly on said member with which the bracelet link may selectively engage to determine its position, said means including a portion integral with the section extending toward the member and portions integral with the member extending toward the section back of which the link may selectively engage, said portions being all spaced inwardly from the end of said section and member.

6. In a foldable buckle, a section, a pivoted member in said section to confine between it and the section a bracelet link, and 120 125 130

adjustment means partly on said section and partly on said member with a selective part of which the bracelet link may engage to determine its position, said means including a portion integral with the section extending toward the member and portions integral with the member extending toward the section back of which the link may selectively engage, said portions being all spaced inwardly from the end of said section and member, and hook means at the ends of said section and member for an additional position of adjustment, and a second section hinged to the first section to fold over the said member and maintain it in link confining position.

7. In a foldable buckle, a section, a pivoted member in said section to confine between it and the section a bracelet link, and adjustment means partly on said section and partly on said member with a selective part of which the bracelet link may engage to determine its position, said means including a portion integral with the section extending toward the member and portions integral with the member extending toward the section back of which the link may selectively engage, said portions being all spaced inwardly from the end of said section and member, and hooks at the ends of said section and member for an additional position of adjustment, said hooks cooperating to hold the member and section in closed position, and a second section hinged to the first section to fold over the said member and maintain it in link confining position.

8. In a foldable buckle, a section, spaced hooks on said section with either one of which a bracelet link may engage and a cover member hinged to said section to extend over said hooks and hold the link in engagement with its selected hook, and a second section hinged to the first section to fold thereover and maintain the cover member in closed position, and means to connect another bracelet link to the free end of said second section, whereby the sections with the bracelet connected thereto may be swung to an end-to-end extended position to enlarge the encircling size of the bracelet.

9. In a foldable buckle, a section, spaced hooks on said section with either of which a bracelet link may engage, one hook being bent up at the end of said sections and the other hook spaced inwardly therefrom, and a cover member hinged to said section to extend over said hooks and hold the link in engagement with its selected hook, and a second section hinged to the first section to fold thereover and maintain the cover member in closed position, and means to connect another bracelet end to said second section.

10. In a foldable buckle, a section, spaced hooks on said section with either of which a bracelet link may engage, one hook being

bent up at the end of said sections and the other hook spaced inwardly therefrom, and a cover member hinged to said section to extend over said hooks and hold the link in engagement with its selected hook, and means to connect another bracelet end to said second section, said cover having a hook at its end to snap over the end hook on said section and hold the same in closed position, and a second section hinged to the first section to fold thereover and maintain the cover member in closed position.

11. In a foldable buckle, a section, spaced hooks on said section with either of which a bracelet link may engage, one hook being bent up at the end of said sections and the other hook raised from the stock of said section at a point spaced inwardly therefrom, and a cover member hinged to said section to extend over said hooks and hold the link in engagement with its selected hook, and means to connect another bracelet end to said second section, said cover having a hook at its end to snap over the end hook on said section and hold the same in closed position, and a second section hinged to the first section to fold thereover and maintain the cover member in closed position.

In testimony whereof I affix my signature.

MAURICE ANDERSON.
